Benjamin R. Singer, Bronx, N. Y.

Application August 18, 1944, Serial No. 114,931

Term of patent 7 years

(Cl. D83—8)

To all whom it may concern:

Be it known that I, Benjamin R. Singer, a citizen of the United States, residing at the Bronx, New York, in the county of Bronx and State of New York, have invented a new, original, and ornamental Design for a Baby Bottle Holder, of which the following is a specification, reference being had to the accompanying drawing, forming a part thereof.

In the drawing:

Fig. 1 is a side elevational view of a baby bottle holder, showing my new design;

Fig. 2 is a top plan view and

Fig. 3 is a side elevational view of the same.

I claim:

The ornamental design for a baby bottle holder, as shown.

BENJAMIN R. SINGER.
